UNITED STATES PATENT OFFICE.

SAMUEL A. BOUCHER, OF BARTON, MARYLAND.

CORPSE-COOLER.

SPECIFICATION forming part of Letters Patent No. 710,745, dated October 7, 1902.

Application filed February 20, 1902. Serial No. 94,900. (No model.)

To all whom it may concern.

Be it known that I, SAMUEL A. BOUCHER, a citizen of the United States of America, residing at Barton, in the county of Allegany 5 and State of Maryland, have invented certain new and useful Improvements in Corpse-Coolers, of which the following is a specification, reference being had therein to the accompanying drawings.

10 This invention relates to certain new and useful improvements in corpse-coolers, and relates more particularly to a refrigerating device for undertaker's use for the preserving of dead bodies by means of a refrigerating or 15 cooling agent.

The present invention has for its object to provide a device of the above-described character that will be extremely simple in construction, strong, durable, comparatively inexpensive to manufacture, and highly efficient in its use.

A still further object of the invention is to provide a waterproof covering in combination with a mask in order to retain the life-like features of the corpse.

25 The invention still further contemplates to provide a covering of waterproof material having openings formed therein in order that the space between the corpse and the inner 30 lining may be easily accessible for the purpose of placing ice therein and also provide means for closing said openings.

With the above and other objects in view the invention consists in the novel combination 35 and arrangement of parts to be herein-after more fully described and specifically pointed out.

In describing the invention in detail reference is had to the accompanying drawings, 40 forming a part of this specification, and wherein like numerals of reference indicate like parts throughout the several views, in which—

Figure 1 is a vertical sectional view of my improved device as it appears when in use. 45 Fig. 2 is a top plan view of the same, showing it closed. Fig. 3 is an enlarged side elevation of the mask.

In the drawings the reference-numeral 1 represents the cooling table or base, and 2 the 50 corpse, the latter being inclosed in a bag 3,

formed of waterproof material, said bag having formed therein openings 4 and 5. These openings may be closed in any suitable manner, but are preferably secured by means of cords 6 and 7. The drain-pipe 8 may be attached to any convenient place at the bottom of the bag in order to allow the drippings caused by the melting of the ice to be carried off from the bag. The ice or cooling agent is represented by the reference-numeral 9 and 55 is placed between the inner side of the bag and the corpse. The mask 10 is formed of any suitable material and carries a bearing 11, through which extends a set-screw 12, carrying on its opposite end a head 14. The 60 said head 14 is adapted to bear against the chin of the corpse in order to retain the lower jaw and mouth in proper position.

The reference-numeral 15 represents a head-rest or pillow, which is likewise constructed 70 of waterproof material, upon which the head and mask rest.

The many advantages obtained by the use of my improved device will be readily apparent from the foregoing description, taken in 75 connection with the accompanying drawings.

It will be noted that various changes may be made in the details of construction without departing from the general spirit of my 80 invention.

Having fully described my invention, what I claim as new, and desire to secure by Letters Patent, is—

A corpse-cooler comprising a bag of waterproof material having parallel sides and 85 rounded ends, said bag having its upper side provided with two elongated spaced-apart slits, one of said slits being arranged adjacent the forward end of the bag, an outlet-tube arranged adjacent the lower end of the bag, and 90 cords attached to the bag adjacent the said slits for closing the same, substantially as described.

In testimony whereof I affix my signature in the presence of two witnesses.

SAMUEL A. BOUCHER.
